UNITED STATES PATENT OFFICE

2,666,953

METHOD OF MAKING PARTITIONED
CONTAINERS

Mary M. Andrews, Akron, Ohio, assignor, by
mesne assignments, to The B. F. Goodrich
Company, Akron, Ohio, a corporation of New
York

Application February 17, 1950, Serial No. 144,683

3 Claims. (Cl. 18—58.7)

1

This invention relates particularly to the method of making a container.

An object of this invention is to provide a simple and inexpensive method of making a flexible resilient carrying bag.

Other objects of this invention will be apparent from the description and drawings which follow.

Partitions in carrying bags of conventional construction are stitched together to form compartments. Even when water impervious materials are employed in making such a bag the needle holes necessarily present permit seepage of water from one compartment to another, and frequent repairs are necessary, since the stitches soon pull apart causing the compartments to lose their continuity. Furthermore, such a construction requires a considerable amount of labor in its manufacture because of the cutting and sewing required.

I have invented a partitioned container in which the compartments are impervious to liquid and are integral with the remainder of the container permitting wet articles to be placed in a compartment adjacent to a compartment containing dry articles without water diffusing from one compartment to another. Stitching is not required in forming the compartments of the container eliminating disadvantages encountered in stitched articles. A partitioned container formed in accordance with my invention comprises a unitary body member having at least one in-turned wall portion forming one or more compartments, said body member being constructed of a water impervious material.

The embodiment shown in the appended drawings and described below is intended to serve as an illustration and not as a limitation of the invention.

In the drawings:

Fig. 1 is a view in perspective of a partitioned carrying bag embodying this invention;

Fig. 2 is a section on line 2—2 of Fig. 1;

Fig. 3 is a section on line 3—3 of Fig. 1; and

Fig. 4 is a side elevation partly broken away and in section of the body member of the carrying bag in an intermediate stage of manufacture.

As shown in Fig. 1 body member 10 of the carrying bag is formed of a single relatively thin wall member 11 of a rubber or rubber-like material. The partition 12 which may be divided into a plurality of compartments 13, 13 is invaginated within body member 10 to a concave generally bulbous configuration as shown in Figs. 1 and 3, forming compartments into which articles may be placed.

Slit openings 14, 14 in partition member 12 per-

2

mit ingress to the inner compartment 15. Slide fasteners 16, 16 provide means for sealing openings 14, 14.

Handles 17, 17 are secured to body member 10 to facilitate transporting the bag.

It is preferable to have a flexible resilient springy frame member 18 adhered or attached to body member 10 along the upper margins of the container to normally maintain the bag substantially closed. Frame member 18 may be constructed of any springy material such as spring steel, wood, rubber, etc., and may be affixed to body member 10 by any desired method, such as by a cementing process, intertwining the frame member 18 with the body member 10, stapling, etc.

The wall 11 of the article may be formed of any rubbery or rubber-like material having the desired properties of waterproofness and resiliency, such as natural or synthetic rubber, plasticized vinyl resins or the like. When natural or synthetic rubber is used, it is preferably vulcanized.

The preferred method of making a flexible resilient partitioned carrying bag embodying this invention is to form wall member 11 directly from an aqueous dispersion of a rubber-like material.

Wall member 11 is preferably made by dipping a form 19, as shown in Fig. 4, having the desired configuration in a coagulant, such as aqueous acetic acid, a solution of calcium nitrate in acetone, etc., and then immersing the coagulant coated form 19 in an aqueous dispersion of a rubber-like material such as rubber latex for a sufficient period of time (1-15 minutes or more) to build up a deposit of rubber solids of the desired thickness by diffusion of the coagulant into the latex. A body member wall thickness of approximately $\frac{1}{32}$ " is satisfactory. If desired, the coated form is heated to dry the deposit and/or to vulcanize the rubbery material.

40 The form preferably has the configuration shown in Fig. 4 in which the portions of the wall member which are ultimately to constitute compartments 13, 13 extend outwardly from the body member in order to facilitate manufacture.

45 The deposit or body member 10 is stripped from form 19. Frame member 18 is secured to body member 10 and the opening in body member 10 through which shank 30 of form 19 extended is sealed, for example with an adhesive cement, forming seam 21. Openings 14, 14 which are relatively long as compared to their width are formed in body member 10 by slitting wall member 11 of body member 10, and sealing or fastening means 16, 16 are attached.

55 Handles 17, 17 are secured to body member 10

and the desired decorative coloring is sprayed or brushed onto the article.

Since the rubber-like materials from which the partitioned container is formed are not readily deteriorated by water the article may be washed as often as desired, and to facilitate washing and drying the compartments of the container the portion of the container normally invaginated within the body member of the article may be turned outward.

Partitioned carrying bags embodying this invention do not require stitching in the formation of the article. For this reason, said article has excellent durability. Carrying bags of conventional construction require that frequent repairs be made to the stitching which readily deteriorates and breaks especially when such stitching frequently becomes wet or damp. Such a carrying bag having a unitary integral wall composed of a rubbery material will outwear a carrying bag constructed in the conventional way.

The compartments of a carrying bag constructed in accordance with my invention are water impervious which prevents water from diffusing from one compartment to another, thereby permitting wet and dry clothes to be carried in the same bag with assurance that the dry clothes will not become damp because of the wet articles being in close proximity. A bag of this type is particularly useful as a beach bag, in that, wet swimming apparel may be placed in one compartment and dry articles in another compartment without danger of the dry articles becoming damp. It may also be used as a baby utility bag for carrying diapers, etc.

The container may be made in a variety of colors by adding the appropriate dye or coloring material to the rubber-like material from which the body member is formed.

It is clear that obvious modifications and variations may be made without departing from the spirit and scope of this invention as defined in the appended claims.

I claim:

1. The method of making a multiple-compartment handbag which comprises forming a hollow body member having a unitary flexible rubber-like wall, forming a closed-bottom inner compartment encompassed by a closed-bottom outer compartment in said body member by invaginating a portion of said wall of said body member to a position in which the inturned portion of said wall inherently remains invaginated, forming an opening in said wall to provide access into the interior of said hollow body member, and providing means at the upper margins of said handbag for maintaining the mouth of said inner compartment of said handbag normally substantially closed.

2. The method of making a multiple-compartment handbag which comprises forming a hollow body member having a unitary flexible rubber-like wall member by depositing a layer of

rubber-like material on the surface of a form from an aqueous dispersion of said rubber-like material, removing said form from said deposit, sealing the opening through which said form was withdrawn, forming a closed-bottom inner compartment encompassed by a closed-bottom outer compartment in said body member by invaginating a portion of said wall member to a position in which the inturned portion of said wall member inherently remains invaginated, forming an opening in said wall member to provide access into the interior of said hollow body member, and providing means at the upper margins of said handbag for maintaining the mouth of said inner compartment of said handbag normally substantially closed.

3. The method of making a multiple-compartment handbag which comprises forming a hollow body member having a constricted mid-portion and a unitary flexible rubber-like wall member by depositing a layer of rubber-like material on the surface of a form from an aqueous dispersion of said rubber-like material, removing said form from said deposit, securing inside said body member along said wall member adjacent said mid-portion thereof a springy frame member adapted to maintain said handbag substantially closed, sealing the opening through which said form was withdrawn, forming a closed-bottom inner compartment encompassed by a closed-bottom outer compartment in said body member by invaginating a portion of said wall member to a position in which the inturned portion of said wall member inherently remains invaginated, forming an opening relatively wide as compared to its width in said wall member to provide access into the interior of said hollow body member, providing means for closing said opening into said body member, and securing to said body member means for facilitating the carrying of said handbag.

MARY M. ANDREWS.
